DOOR FASTENER

George W. Slopa and Robert E. Slopa, Harvard, Ill.

Application August 23, 1955, Serial No. 530,076

3 Claims. (Cl. 292—79)

This invention relates to door fasteners and particularly to fasteners for refrigerator doors and the like.

In order to minimize warpage of the door and provide a tight seal around the periphery of the latter, a plurality of fasteners are frequently located to engage the periphery of the door at spaced points thereon, which fasteners are moved into and out of position in engagement with the door in response to opening and closing of the door and are arranged to yieldably urge the door against the frame. It is an important object of this invention to provide an improved door fastener of the type referred to above in which the pressure applied to the door by the fastener can be readily adjusted without disassembling the fastener from its mounting.

Another object of this invention is to provide a fastener for applying pressure to the free edge of the door which is of simple and compact construction having few operating parts and which is durable and efficient in use.

A further object of this invention is to provide an improved mounting for the fastener and the strike plate to permit positive adjustment of the position of the fastener and strike plate to adapt the same for different applications, and to accommodate changes in the door and door sealing gasket which occur during use.

These, together with various ancillary objects and advantages of this invention will be more readily appreciated as the same becomes better understood by reference to the following detailed description when taken in connection with the accompanying drawings:

Figure 1 is a plan view of the fastener;

Fig. 2 is a plan view of the keeper;

Fig. 3 is a sectional view through the fastener and keeper;

Fig. 4 is a fragmentary view through the mounting flange on the door fastener, taken on the plane 4—4 of Fig. 1; and

Fig. 5 is a perspective view of one of the locking pads for retaining the fastener in a preselected adjusted position.

Reference is now made more specifically to the door fastener 8 and keeper 9 shown in the accompanying drawings. The fastener includes a housing having spaced side walls 10, a top wall 11 and a rear wall 12. The housing is open at the front and bottom thereof and is formed with outwardly extending mounting flanges 13 formed on the lower ends of each of the side walls. The flanges are arranged for mounting the door fastener on the frame 15, of a cooler or the like, and are preferably formed with elongated openings 16 for the reception of a lag screw or bolt 17. In order to permit adjustment and positive locking of the door fastener in a preselected position on the frame, the upper surfaces of the flanges 13 are serrated in a direction transversely of the opening 16, as indicated at 18 and a pad 19 having complementary serrations 20 formed on the under surface thereof is disposed on the bolt or lag screw 17 and arranged to engage the serrations in the mounting

2

flanges. As the lag screw is tightened, the serrations on the pad and flange intermesh and thereby lock the fastener in its adjusted position.

A latch member 22 is disposed within the housing 5 between the side walls 10 and formed with an enlarged boss 23 adjacent one end thereof for the reception of a pivot pin 24. The pivot pin extends through openings in the side walls 10 of the housing, which openings are located adjacent the lower front corner of the side walls 10 whereby the latch member is swingably supported on the side walls for movement therebetween. A pair of spaced ears 26 are formed on the latch member 22 and extend forwardly therefrom, as best shown in Figs. 1 and 3. A roller 27 is disposed between the ears 26 and journaled on a pin 28 carried by the ears.

Provision is made for yieldably urging the roller on the latch member into engagement with the keeper and for this purpose, an arm 31 is formed on the latch member 22 and extends transversely thereof into the housing 20 in spaced relation to the top wall 11. A spring 32 is disposed in the housing and engages the latch arm to urge the latter in a counterclockwise direction as viewed in Fig. 3 to thereby move the roller 27 outwardly of the housing. As shown, the spring 32 is a coil spring which engages the underside of the arm 31 and, in accordance with the present invention, provision is made for adjusting the compression of the spring 32 to thereby selectively vary the pressure applied by the roller. For this purpose there is provided a bolt 34 which loosely extends through an opening 35 in the top wall 11 and through an elongated opening 36 in the arm 31 into the housing. An abutment 37 here shown in the form of a nut having an integral collar 38 formed thereon is threadedly attached to the threaded lower end 39 of the bolt to permit adjustment of the abutment toward and away from the arm 31. The spring 32 is disposed around the collar 38 and around the bolt 34, between the nut 37 and the arm 31. The bolt 34 is arranged to be turned by means of the head 34a thereon located externally of the housing. A tongue 41 is provided on the latch member 22 to extend rearwardly thereof, and has a face 41a on the rear edge thereof engageable with the periphery of the nut 37 to prevent rotation of the latter when the bolt is turned to adjust the position of the abutment.

The keeper 9 is adapted to be mounted on a door 46 which, as shown, is of the type which overlaps the frame 15. As is conventional, a sealing gasket or strip 47 is interposed between the door and the frame to form a seal thereat when the door is closed. The keeper includes a mounting base 48 having a transversely extending channel 49 formed integrally therewith. A block 51 is slidably disposed in the channel and a nose portion 52 is formed on the block and positioned to engage the roller 27 of the fastener. In order to permit the block and keeper to be adjusted and positively locked in an adjusted position with respect to the door, the inner face of the channel 49 is transversely serrated as indicated at 53 and the registering face 54 of the block is correspondingly serrated to provide interlocking teeth on the abutting faces. Studs 55 extend through elongated slots 56 in the channel and are threaded into the block 51 to draw the serrated faces of the block and channel together and secure the block 60 in its adjusted position.

The nose portion 52 of the keeper is formed with beveled faces 57 and 58 which intersect in a tip portion 59. The beveled face 57 is arranged to engage the roller 27 as the door 46 is moved to its closed position to cam 70 operate the roller out of the path of movement of the keeper. As the tip portion 59 passes the high point of

the roller, the roller moves outwardly over the beveled surface 58 to the position shown in Fig. 3.

A stop is provided for limiting movement of the latch member outwardly of the housing and, as best shown in Fig. 4, includes a pair of inwardly extending flanges 61 on the side walls adjacent the open end of the housing, which flanges are disposed in the path of movement of the latch member.

From the foregoing it is apparent that the spring 32 extends alongside the latch member 22 and engages the arm 31 which extends transversely of the latch member thereby providing a compact latch arrangement. The latch member, arm and spring are mounted in an enclosing housing in a manner to permit adjustment of the compression of the spring from externally of the housing. Further, the housing is mounted for adjustment in the plane of the door frame for adjustment toward and away from the door to accommodate expansion or contraction of the latter and the keeper is mounted for adjustment in a direction transverse to the plane of the door to compensate for changes in the thickness of the door seal gasket and the like, as occur during use.

We claim:

1. A door fastener comprising a housing having spaced side walls and a top wall and open at the front thereof, an L-shaped latch member including first and second legs, said first leg extending along the open front of said housing between said side walls, means pivotally mounting the free end of said first leg on said side walls adjacent said open front of the housing and at a point remote from said top wall, said second leg extending transverse to said first leg into said housing in spaced relation to said top wall, a roller mounted on said latch member at the junction of said legs and projecting through the open front of said housing, said second leg having an opening therein adjacent the end remote from said open front of the housing, a bolt extending through said top wall and through said opening in said second leg and into said housing alongside said first leg, a spring disposed around said bolt and engaging the underside of said second leg for urging the latch member in a direction to move said roller out of the open front of said housing, and a nut threaded on said bolt engaging the lower end of said spring to permit adjustment of said spring in response to turning of said bolt.

2. A door fastener comprising a housing having spaced side walls and a top wall and open at the front thereof, an L-shaped latch member including first and second legs, said first leg extending along the open front of said housing between said side walls, means pivotally mounting the free end of said first leg on said side walls adjacent said open front of the housing and at a point remote from said top wall, said second leg extending transverse to said

first leg into said housing in spaced relation to said top wall, a roller mounted on said latch member at the junction of said legs and projecting through the open front of said housing, said second leg having an opening therein adjacent the end remote from said open front of the housing, a bolt extending through said top wall and through said opening in said second leg and into said housing alongside said first leg, a spring disposed around said bolt and engaging the underside of said second leg for urging the latch member in a direction to move said roller out of the open front of said housing, a nut threaded on said bolt engaging the lower end of said spring to permit adjustment of said spring in response to turning of said bolt, and a tongue formed on said first leg engageable with said nut to prevent turning of the latter as the bolt is turned to vary the compression of the spring.

3. A door fastener comprising a housing having spaced side walls and a top wall and open at the front thereof, an L-shaped latch member including first and second legs, said first leg extending along the open front of said housing between said side walls, means pivotally mounting the free end of said first leg on said side walls adjacent said open front of the housing and at a point remote from said top wall, said second leg extending transverse to said first leg into said housing in spaced relation to said top wall, a pair of spaced ears formed on said first leg adjacent the junction of said first and second legs and extending from the side of said first leg opposite said second leg, a roller mounted between said ears and projecting through the open front of said housing, said second leg having an opening therein adjacent the end remote from said open front of the housing, a bolt extending through said top wall and through said opening in said second leg and into said housing alongside said first leg, a spring disposed around said bolt and engaging the underside of said second leg for urging the latch member in a direction to move said roller out of the open front of said housing, and a nut threaded on said bolt engaging the lower end of said spring to permit adjustment of said spring in response to turning of said bolt.
